UNITED STATES PATENT OFFICE.

PATRICK T. LEAHY, OF CLEVELAND, OHIO.

MIXING VALVE.

1,427,606.

Specification of Letters Patent. Patented Aug. 29, 1922.

Application filed September 29, 1919, Serial No. 327,187. Renewed March 6, 1922. Serial No. 541,587.

To all whom it may concern:

Be it known that PATRICK T. LEAHY, citizen of the United States, residing at Cleveland, in the county of Cuyahoga and State of Ohio, has invented certain new and useful Improvements in Mixing Valves, of which the following is a specification.

This invention pertains to an improvement in mixing valves, and my object is to provide an exceptionally simple and inexpensive and relatively small mixing valve especially adapted for use in lavatories, bath tubs, bath showers, etc.

In the drawing accompanying this application, Fig. 1 is an elevation of the dial or index face of the valve. Fig. 2 is a side view of the valve. Fig. 3 is a sectional view centrally through the valve. Fig. 4 is a sectional view transversely through the body 20 of the valve, showing the cut-off position of the valve disk, and Fig. 5 is a similar view with the valve disk turned to a mixing position. Fig. 6 is a perspective view of the valve stem and Fig. 7 a perspective view of the valve disk.

The invention comprises a cylindrical open body 2 having a closed bottom 3 with a flat upper surface adapted to provide a relatively large sealing seat for a round flat 30 valve disk 4. Body 2 also has a rib or projection extending diametrically across its bottom in which two separate water intake passages 5 and 6 are provided and with which two separate supply pipes are adapted to be connected by screw-engagement at 35 opposite sides of the body. Each passage has a vertical discharge orifice or port at its inner end extending through the bottom 3 opposite valve disk 4, and said valve 40 disk is also provided with a pair of openings adapted to register with said orifices, or ports. These orifices, designated 7 and 8, and separate openings 9 and 10 in the valve disks, are set the same distance from the 45 center or axis of the valve disk, but the openings in the disk and the orifices in the body are off-set relatively to each other in respect to a given center line so as to permit control of the water passing through either 50 orifice singly or both orifices jointly. Thus, the orifices 7 and 8 in the bottom of the body are both located a short distance to one side of a diametrical line extending through the

body, while the openings 9 and 10 in the valve disk are located directly on a diametrical line extending through said disk. 55

When the parts are assembled with the valve disk in a cut-off position the openings 9 and 10 in the disk are distantly removed from the orifices 7 and 8 in the bottom 3 and are located on a diametrical line which is at right angles to the axis or a diametrical line of the water intake passages 5 and 6. One of the openings in the disk, in this instance opening 10, is less than 90 degrees 60 distant from either orifice 6 or 7, whereas the other opening 9 is at a greater distance than 90 degrees from both said orifices, measured by a rotary movement of the valve disk. The result is that less than a quarter 70 turn of the valve disk is required in either direction to open either the hot water or the cold water orifices, while slightly increased rotation of the valve disk from an open position of either the hot or cold water orifice 75 will then bring both openings 9 and 10 in register and open communication with both orifices 7 and 8, thereby permitting the entrance of both hot and cold water into the mixing chamber 11 of the body. Equal 80 amounts of hot and cold water can be taken in by rotating the valve disk so that the openings and orifices provide entrances of equal size, or a different mixture can be obtained by rotating the valve disk either to 85 the right or the left to reduce the size of one of the entrances and enlarge the size of the other entrance simultaneously.

The valve disk is held centrally within the recessed bottom 3 by an annular shoulder 90 12 which is adapted to engage the periphery of the disk, and the central part of the disk is slightly reduced and projected upwardly and provided with a pair of flat sided lugs 14 and 15 arranged on opposite sides of a 95 central round recess or cavity 16 in the upper face of the disk. A round valve stem 17 has a short round projection 18 at its inner end which extends and seats within recess 16, and this stem is interlocked in 100 separable union with the valve disk by an annular flange 19 having notches on opposite sides of the stem to accommodate and receive the lugs 14 and 15. A slight play 105 is afforded between the stem and valve disk to permit the valve disk to always remain

in flat seating relations with the bottom, and the disk is ground to its seat in bottom 3 before the parts are assembled to effect an absolutely water-tight joint. Permanent 5 and effective seating engagement between the valve parts is obtained by a coiled compression spring 20 which rests upon the flange 19 of the valve stem and bears at its upward end against a shoulder 21 in the screw 10 cap or cover 22 which is screw-engaged with the upper open end of the body. The extremity of the valve stem projects through an extension 23 on said cap and through a screw ring or gland member 24 which is 15 adapted to compress and confine suitable packing material 25 about the stem. A handle 26 is detachably fastened to the upper end of the stem and this handle may be provided with a projecting finger 27 adapted 20 to be shifted opposite different index or designating characters on the extended flange or dial ring 28 of the cover or cap so that the operator may be guided in turning the valve disk to an open or closed position, 25 either for delivering hot or cold separately or a mixed discharge of water through the single outlet 29 at one side of body 2.

The device comprises practically only seven pieces or parts, to-wit: body 2, valve 30 disk 4, stem 17, spring 20, cap 22, gland member 24, and handle 26. Body 2 is plain and a simple and inexpensive member to cast and produce; the relatively large flat seat is accessible through the relatively large 35 and wide open chamber and end of the body; the valve disk and its separate stem are easily fitted to each other and to the body and also adapted to accommodate a slight irregularity of movement between the parts; 40 and the coil spring bars centrally down upon the valve stem and holds the valve disk

firmly to its seat in all of its rotative movements.

What I claim is:

1. A mixing valve comprising an open 45 body having a side outlet and a flat inner bottom surface provided with a pair of separate intake ports, a valve disk having openings adapted to register with said ports and provided with a lug at one side on its top, 50 a valve stem in separable engagement with said disk having a notched flange adapted to receive and engage said lug, a cap detachably engaged with said body adapted to support said stem, a compression spring 55 sleeved upon said stem between said cap and the flange on the stem, and an operating handle for said stem.

2. A mixing valve comprising a body having a mixing chamber with a discharge outlet and provided with an inner flat recessed surface having a pair of intake ports located in one lateral half thereof, a flat valve disk having a pair of openings located on opposite sides of its center on the diameter of said disk and provided at its upper side with a central recess and lugs at opposite sides of said recess, a valve stem having a rounded projection at its lower end adapted to seat in said recess and provided 70 with a notched annular flange fixed thereon and engaging said lugs, a screw cap for said body having an opening centrally for said valve stem, a compression spring sleeved upon said stem between said cap 75 and valve disk, and an operating handle detachably affixed to said stem outside of said cap.

Signed at Cleveland, in the county of Cuyahoga, and State of Ohio, this 26 day 80 of July, 1919.

PATRICK T. LEAHY.
